PROCESS AND DEVICE FOR OPERATING DIAPHRAGM
METERING PUMPS

The invention relates to a process and apparatus for the operation of a diaphragm metering pump, where the diaphragm displaces with one of its sides the liquid that is to be metered and is acted upon on its other side by a pressure-transmitting liquid, displaced by means of a piston or recuperator piston, whereby flow channels have been provided through which transfer liquid flows from a supply space into the space located between diaphragm and piston or pressure-transmitting space for the purpose of balancing out losses from leakage. The invention furthermore relates to installations for carrying out the process.

In the case of diaphragm metering pumps of the mentioned type, the pumping movement of the diaphragm is not brought about mechanically but hydraulically. This, among others, has the advantage that the diaphragm will be acted upon evenly across its entire useful area and that the volume which it displaces at every stroke will be adhered to exactly once the adjustment of the pump has been set. Since the pressure-transmitting liquid is shifted by means of a reciprocating piston which can never be fitted absolutely tightly into the cylinder bore assigned thereto, and since very high pressures occur frequently, losses of transmitting liquid from leakage are unavoidable. Therefore, in the case of every stroke, the transmitting liquid is sucked up. This will be achieved in the case of a pump with nonrevolving pistons with the provision of a longitudinal bore and a transverse bore bisecting the former, will be arranged in the piston whereby the transverse bore is released by the cylinder bore in the dead point of the piston on the suction side. As a result thereof, a connection between the supply space and the pressure-transmitting space will be established, so that possible losses through leakage can be replaced. In the case of revolving pistons, the flow path can be opened since the transverse bore in the piston, which is also present in this case, is temporarily covered by a longitudinal groove in the cylinder. Finally, the filling-up may also be accomplished by means of a flow valve. During the operation of such pumps it turned out that, upon conveyance of very small quantities per stroke of the pump, these quantities change in the course of time. One cannot utilize these changes whenever the ratios of quantity must be maintained.

An object of the present invention is to provide processes for the operation of the mentioned type of pumps so that even with very small conveyed quantities per stroke, said quantities will remain permanently constant.

It is therefore a further object of the invention to provide as a first process, that the transmitting liquid be fed with a higher pressure to the pressure-transmitting space than the pressure prevalent in the supply space. According to a further process, the transmitting liquid is filled into the supply space in a well-degassed state and is protected against contact with the surrounding air.

Both solutions are premised with the realization that the inaccuracies originate since the gases, especially air, have been dissolved in the pressure-transmitting liquid with these gases forming little gas bubbles because of the underpressure developing during the sucking-in into the pressure transmitting space. This can be explained if one considers that the quantity of solution of gas in oil obeys Henry's Law, according to which $m=kp$, wherein m is the mass of gas, k a constant and p the absolute pressure. If the oil supply container comes into contact with the ambient air, which indeed has a pressure of about 1 atmosphere, then a certain mass of gas m may dissolve. During repeated suction there now develops a pressure which is less than 1 atmosphere. When the transmitting liquid, i.e., hydraulic oil, has already been saturated completely or approximately with gas in the supply space, then the quantity of air can no longer be held at the lower pressure and individual small gas bubbles will develop. Since these small gas bubbles are then compressed in the course of the pressure

stroke and will again partially dissolve, differences concerning the movement of the diaphragm will develop. The more gas which is compressed during successive sucking-in, the smaller the conveying volume of the pump will be. As mentioned, the present invention makes use of this realization and provides two processes with which the emergence of gas from the pressure-transmitting liquid will be avoided.

With the first process, a lower pressure prevails in the supply container than in the pressure-transmitting space. Even if the pressure-transmitting liquid in the supply space is saturated with air, no escape of gas can occur during the refilling of the pressure-transmitting space, since the pressure therein is indeed higher than in the pressure-transmitting space; thus the state of saturation, which indeed is in proportion to the absolute pressure, will not be reached at all. With the other proposal according to the invention, only well-degassed pressure-transmitting liquid will be used *a priori* and care is taken that this pressure-transmitting liquid will not be able to absorb any air or other gas in the course of time. Experiments have proven that in the case of such a mode of operation of the pump, even small deliveries can be maintained precisely over long periods of time.

A device according to the invention for carrying out the first-mentioned process, i.e. the process wherein the pressure in the supply container is lower than it is in the course of refilling, is characterized by the fact that a charging pump is associated with the metering pump whose suction side is connected with the supply space, being under atmospheric pressure, for the transmitting liquid and whose pressure side is connected with a space or refill space, from which the pressure-transmitting space is refilled. Even if pressure-transmitting liquid should be sucked into the charging pump, which is saturated with air or some other gas, no air can escape during refilling, since a higher pressure will be produced in the charging pump which, as a consequence, the hydraulic liquid will be undersaturated.

In embodiment of the invention, the charging pump has been connected into a unit with the remaining metering pump. This has the advantage that a separate charging pump aggregate need not be set up.

Therefore, the charging pump will be driven by the same drive as the piston, displacing the transmitting liquid. As a result any need for a separate drive will be saved.

Preferably the charging pump is a reciprocating pump whose piston is arranged equiaxially in relation to the piston displacing the transmitting fluid and is connected indirectly or directly with said piston. As a result thereof a particularly simple construction can be obtained, since the same driving system serves both for the drive of the recuperator piston and the drive of the piston of the charging pump. Basically, however, it would also be possible to use a geared pump as a charging pump, which is driven by the same motor which also drives the driving mechanism for the recuperator piston.

A spring-loaded buffer piston may be series connected with the piston of the charging pump, whereby said buffer piston cooperates with an overflow bore leading to the suction side of the charging pump, in such a way that the buffer piston will release the overflow bore after reaching a certain volume on the pressure side of the charging pump. The use of such a spring-loaded buffer piston will permit the pressure to be kept constant in the refill space, so that thus precisely defined conditions will prevail.

According to a further development of the invention, a closeable bypass line leads from the pressure side of the charging pump to the suction side. With the aid of such a bypass line the effect of the charging pump can be cut off in such a manner that, although the charging pump continues to operate, the charging pump will produce an excess pressure in the refill space. This switching off has the advantage that, with larger deliveries which will be maintained precisely enough even without excess pressure in the refill space, one will avoid the filling up pressure. This may sometimes be advantageous since, on the conveying side of the diaphragm, only low pres-

sures prevail, as an initial stress of the diaphragm through the charging pressure is undesirable.

Advantageously the flow path which exists with an open bypass line has been shifted in such a manner that the transmitting liquid is not injected into air spaces. As a result thereof, a frothing of the pressure-transmitting liquid, which indeed favors an air enrichment, will be avoided.

A device to carry out the second process in which a well-degassed pressure-transmitting liquid is filled into the pump and the subsequent enrichment of gas is avoided is characterized by the fact that, immediately at the surface of the oil level in the supply space, which is connected with the atmosphere, or at a short distance from this oil level, a diaphragm has been disposed which seals the oil supply in an air tight manner. Such a construction has the advantage that the effect of the pump of this driving mechanism may take effect despite the sealing-off of the space for the oil supply, which in the case of such pumps, generally speaking, is open to the outside. The displacement in this case executes a kind of breathing movement which corresponds to the frequency of the pump.

Further objects of the invention will be apparent from the following description when considered in connection with the accompanying drawing in which;

FIG. 1 is a longitudinal section through the pump, and

FIG. 2 is a cross section taken on the line II-II OF FIG. 1 in the direction of the arrows.

The pump according to the invention comprises four main parts, namely, a driving mechanism part 1, a part 2 containing the supply space for the pressure-transmitting liquid, a part 3 containing the charging pump together with attachments, and a front part 4 containing the actual metering pump.

An electric driving motor, which has not been shown on the drawing, has been arranged on the driving part 1, which motor drives the eccentric shaft 5. On this eccentric shaft an eccentric 6 is seated, which places the driving rod part 7 in a reciprocating motion. A further part or link 8 of a driving rod is connected by means of a joint bolt 9 with the driving rod part 7. The driving rod part 8 has been articulated, which has been mounted rotatably at point or bolt 13. The joint bolt 13 is on an adjusting element 15, which can be swiveled around a bolt which has been firmly arranged on the drive housing 16. The bolt, viewed in FIG. 1 in its operating condition coincides with the bolt 9. A fishplate 18 is articulated at point 17 to the adjusting part 15, which plate is attached articulately to a spindle nut 19. The spindle nut 19 may be adjusted by turning spindle 20 by means of the adjusting knob 21. The position of the spindle nut and thus the adjustment of the pump at large can be read with the help of a pointer 22 through a window 23.

Upon swiveling the adjusting part 15, the position of point 13 changes, around which the fishplate 12 swivels. The fishplate 12 guides the center of gravity on a circular arc and, depending on the position of said circular arc, a greater or lesser stroke of the guide 11 will be obtained. Independently of any shifting, the rear center of gravity remains constant, which will be achieved by the suitable dimensioning of the various members of the drive. The drive does not constitute an object of this invention.

The center part 2 is constituted essentially by a housing 24 which has an opening 25, which is open to the atmosphere. Inside the housing 2, there is the supply space 26 for the pressure-transmitting fluid 27. The fluid is filled in through an opening 25 and may be drained by means of a closing screw stopper 28. For the purpose of sealing space 26 as against the drive housing, a gasket 29 has been provided.

In the pump part 3, a cylinder bore 30 for the cylinder piston 31 of the charging pump has been provided and the piston 31 is integrally connected with guide plunger 11. For sealing the space 34 from space 26, there is provided a gasket 33 arranged in an annular groove. The piston 31 during its reciprocating movement plunges into the pump space 34 and a suction valve 35 and a pressure valve 36 are provided for the pump space 34. A suction channel 37, which penetrates the

entire housing 38 of the pump part 3, leads from the supply space 26 to the suction valve 35 and empties at its left end into an annular groove 39 arranged on the front side of the housing 38. The suction valve has a valve ball 40 as a closing element, which is capable of closing bore 41.

Pressure valve 36 disposed in a manner similar to suction valve 35. A pressure gauge 41 has been arranged above the pressure valve 36. A bore 42, which has been closed on the right-hand side by means of a stopper or plug 43, and a bore 44 lead from the pressure valve 36 into a space 45 as a refill space. The refill space 45 cooperates with a buffer piston 46, which is pressed downwards with a certain force by means of a spiral spring 47. The spiral spring 47 is supported on top against an adjusting screw 48, which can be secured by means of a nut 49. A ventilation bore 51 empties between piston 46 and the adjusting screw 48 into a bore 50 in which the buffer piston slides, which ventilation bore 51 enters with its opposite right-hand end into the supply space 26 open to the atmosphere. Further below, a bore 52 has been arranged which empties into the annular groove 39.

Starting out from space 45, a bore 53, see also FIG. 2, leads by means of a bore 54, running at right angles thereto, into the annular groove 39, so that space 45 will be connected with the suction side. However, this connection may be closed with the aid of ball 55, which can be pressed firmly against the shoulder in bore 53 by means of a screw bolt 56.

The thin piston 58, displacing the transmitting liquid for the purpose of operation of the pump diaphragm or washer 57, has been mounted on the piston 31 of the charging pump by means of a cross pin 59. This thin piston 58 slides in a thin bore 60 of an inserted element 61 in which sealing rings 62 and 63 are disposed for purposes of sealing it from space 34. The front end of piston 58 slides in a bushing 64. A longitudinal bore 65 and a transverse bore 66 have been arranged in the piston 60. Between the insert 64 and insert 61 a free space 67 has been provided, which communicates with the refill space 45. On the left side of part 38 there is a gasket 32 which seals space 45 from space 39.

The bore 68, in which the thin piston 58 slides, has been closed in front by means of a plate 69, which has a small bore 70 therein. The diaphragm 57 is supported in the suction side dead point at the face of insert 64, which for this purpose has been made slightly concave, and at the closing plate 69. The oil moved by piston 58 can enter only by means of the small bore 70 into the space on the right-hand side of the diaphragm.

An intermediate element 71 has been placed on the housing 38 which contains the charging pump and is attached by means of screws or bolts 72. On this intermediate piece, the head 73 of the pump is seated and has been attached by means of screws or bolts 74. In this head there is a suction valve 75 and the pressure valve 76, and in this case again, the closing elements are also balls. The connection piece 77 serves for the connection of the pressure line. Slanting bores 80 which lead to the suction valve 75 have been disposed in the pump head 73, which with its right side limits a wall of the pump space 79 and whose other side is limited by the diaphragm 57. Other bores 81 lead to the pressure valve 76 and to the right of the diaphragm, an additional ventilation bore 82 is provided in the insert piece 64, which bore is closed by a ball 84 pressed down firmly by a screw 83, and after loosening the screw creates a connection to the outside.

The pump according to the invention operates as follows. In the case of reciprocating movements of the guide plunger 11, which is placed into a reciprocating motion by the driving system 1, both piston 31 of the charging pump which is connected firmly with plunger 11 and the displaced piston 58 also 70 firmly connected with piston 31 of the charging pump, move back and forth in the same rhythm and with the same stroke. Each time the rear dead point has been reached (position drawn), the transverse bore 66 in the piston 58 arrives in the drawn position in which it communicates with space 67 forming a part of the refill space 45 between insert pieces 61 and

64. In the case of the reverse motion, that is to say upon its movement to the right, piston 31 of the charging pump has sucked in pressure-transmitting fluid from the supply container 27 through channel 37 and the suction valve 35. If pistons 31 and 58 move toward the left, then the pressure-transmitting liquid is pushed out from space 34 through pressure valve 36 and reaches the refill space 45 through pressure valve 36 and bores 42 and 44. There, buffer piston 46 is pressed upwards counter to the force of spring 47 and the refill space 45 will be filled up quickly to the point where the buffer piston 46 will be pressed upwards so far that the overflow bore 52 is opened. The excess pressure-transmitting liquid can flow through channel 52 into the annular groove 39 and return from there into the supply container 27 by means of the bore 37, or else is sucked in again immediately by piston 31 of the charging pump. In any case, the refill space 45 will be under the pressure of the spring 47 and this pressure prevails even if the two pistons are in their rear dead point, if for instance, the refill bores 66 and 65 connect space 67 with the high pressure space 68 in front of piston 58. The pressure-transmitting liquid therefore is forced under pressure into the space 68. During the operating stroke, i.e., during movement of the pistons to the left, refill bores 66 will soon be closed and pressure now can build up, which will shift diaphragm 57 toward the left, whereby space 79 is made smaller and the liquid which had previously been sucked in there is conveyed by means of the pressure valve 76 into the pressure line connected at 78. The pressure of the spring 47 is selected in relation to the cross section of buffer piston 46 in such a way that a considerably higher pressure prevails in the refill space 45 than in the supply space 26. If, for example, a pressure of about 1 atmosphere prevails in the supply space, then one should select the pressure in space 45 at about 2 atmospheres. Since, as explained already, the absorptive capacity of a liquid for gases obeys Henry's Law $m=k \cdot p$, there will therefore be an undersaturation in space 45, even in the case where the liquid in space 27 had been saturated with gas, so that a degassing cannot take place. As a result thereof, one will obtain a delivered quantity which remains exactly the same for the product that is to be moved by the diaphragm 57.

If the effect of the charging pump is to be cut out, that is to say, if no pressure is to be maintained in space 45, then the

screw 56 will be unscrewed by a few turns, so that ball 55 will lift off and release bore 53. The liquid forced by piston 31 of the charging pump can then flow back directly to the suction side, that is to say, the flow back no longer takes place by means of the overflow bore 52 but it takes the path of least resistance, namely the path through bore 53 and 54 to the nut 39 and channel 37. No pressure can build up any longer in space 45 and thus the effect of the charging pump is switched off.

I CLAIM:

1. A pump apparatus for metering a quantity of liquid, comprising:

a supply chamber for containing the liquid under atmospheric pressure;

a charging pump piston means for transferring liquid from said supply chamber to a pump chamber through a suction valve during its suction stroke;

a pressure valve through which said piston means transfers liquid from said pump chamber to a refill chamber maintained under pressure and into a pressure transfer chamber during its pressure stroke;

an unsupported diaphragm disposed at said pressure transfer chamber; and

flow channels interconnecting said refill chamber, said pressure transfer chamber and said supply chamber whereby said transfer liquid may flow into said pressure transfer chamber after completion of the suction stroke at a pressure higher than atmospheric for shifting said diaphragm so as to meter said transfer liquid in a degassed condition by reason of said pressurized refill chamber while any excess pressure liquid may be returned to said supply chamber during the suction and pressure strokes of said piston means.

2. The apparatus according to claim 1 wherein said piston means comprises a reciprocating pump piston and wherein a buffer piston is provided for varying the volume of said refill chamber thereby maintaining a constant pressure therein.

3. The apparatus according to claim 2 wherein said buffer piston is spring loaded and wherein said refill chamber cooperates with an overflow bore leading to said supply chamber whereby said buffer piston may open said overflow bore after reaching a predetermined volume during the pressure stroke of said piston means.
